PROGRAM PHASE REVERSER

Jarrett L. Hathaway, Manhasset, N. Y., assignor
to Radio Corporation of America, a corpora-
tion of Delaware

Application June 30, 1938, Serial No. 216,686

8 Claims.

(Cl. 179—1)

This invention relates to systems for controlling voice signals derived from a microphone or other wave pick-up device where unsymmetric electrical circuits including amplifiers are to be fed by such signals. It has been observed in broadcasting and sound recording practices that the half-cycles of sound waves, particularly when produced by the human voice and by certain musical instruments, are at times considerably greater in peak amplitude in one direction or phase than in the other. When such voice waves are impressed upon amplifiers or other apparatus having greater lee-way in one direction of swing than in the reverse, it is desirable that the maximum peaks be applied in such phase as to deliver maximum undistorted output power.

This application is a continuation-in-part of my co-pending application, Serial No. 167,709, filed October 7, 1937, for a "Program polarity reverser." Certain improvements and simplifications are, however, disclosed in this application in contrast with the disclosure of the co-pending case.

In broadcasting, sound recording, and in various sound pick-up systems, including public address systems, it has been found that the electrical circuits involved have greater latitude in one phase than in the reverse, that is, linearity in one phase often extends over a greater range in one direction than in the reverse. Therefore, for maximum undistorted speech or program power to be transmitted through such a system, it is essential that the phasing of the voice frequency wave be made such as to place the maximum peaks in the direction of greatest latitude. The human voice often has as much as a two-to-one difference in the peak amplitudes on the positive and negative sides of the sound wave. In normal program work microphones of the so-called "velocity" type are often used, and these microphones are so disposed with respect to the performers that they pick up sound waves from either one or both sides. Maximum peaks of electromotive force excited by a human voice are of one phase for one side of the microphone and the opposite for the reverse side. In a radio broadcast program it is frequently necessary also to shift the circuits or lines from one microphone to another or to change the location of different microphones. As a result frequent phase reversals occur.

It is an object of my invention to provide means in association with a voice frequency amplifier circuit for automatically inverting the phase of the voice waves whenever the amplitude peaks

in one direction do not conform with the non-linear range characteristics of the circuit.

It is a further object of my invention to provide means in a voice transmission circuit whereby maximum peaks of the voice frequency wave are applied in the direction of greatest latitude in the circuit thereby to avoid distortion.

It is a further object of my invention to provide a simple relay circuit arrangement under control of electron discharge tubes whereby phase reversals of the speech waves are made to take place during moments of relative silence so that no disturbance like switching "plops" are heard.

It is a further object of my invention to provide a program phase reversing device which will enable a microphone to be utilized under optimum conditions in connection with an amplifier or speech circuit having a non-linear characteristic such that distortion takes place at a lower amplitude level in one direction than in the reverse; said phase reversing device being adapted to apply to said amplifier a speech wave whose unsymmetric wave peaks are suitably phased for placing these peaks in the direction of greatest latitude.

My invention will now be described in more detail, reference being made to the accompanying drawing, in which the sole figure thereof represents a circuit diagram of a preferred embodiment.

Referring to the drawing, I show a phase reversing system consisting essentially of a double pole double throw system, operated by suitable actuating apparatus. The swinging contacts *a* and *b* of relay *1* act as the switch blades for accomplishing the reversal.

The input transformer primary *2* bridges across the program line whose phase is to be reversed. The voltage from the secondary *3* is adjusted to proper value by potentiometer *4* and applied to the grid of amplifier tube *5*. Plate voltage is supplied to tube *5* through a resistor *6*. Output audio voltage from tube *5* is fed through condenser *7* to a grid *G* in another amplifier tube *8*, whose bias voltage is fed through resistor *9* from the ground. Self bias is employed on tubes *5* and *8* by virtue of resistors *49*, as is conventional. The output from the anode *P* is used to accomplish phase reversal for exciting the grid *G'* of tube *8* by the conventional phase inversion system through resistor *11* and blocking condenser *12*; this grid *G'* being biased through resistor *13*. The anodes *P* and *P'* act in push pull to feed transformer primary *14*, the latter being bridged by load resistors *15* and *16*. The secondaries *17* 55

and 18 supply audio energy to the diode rectifier portions 19 and 20 of the discharge tube 10. These rectify opposite halves of the audio wave. The output voltage of these rectifiers appears 5 across the resistors 21 and 22. Condensers 23 and 24, connected across these resistors store the rectified voltage for an appreciable time before being discharged by the resistors. The two rectifier output load resistors 21 and 22 are connected 10 in series. The rectified potentials developed across these two load resistors are opposed to one another. The resultant voltage is then added to the bias applied through the relay contacts *d* to the grid of tube 25. Audio frequency variations 15 are smoothed out of this grid voltage by resistor 26 and condenser 27. The plate current of tube 25 tends to actuate relay 1. Contact *c* breaks away from its back contact before the breaking of other contacts. This operation serves 20 to accelerate the action of the relay in going from the non-actuated to the actuated position. This action is accomplished by resistor 28 shunting the relay coil, thus robbing some of its current until the contact is broken. When contact 25 *c* closes against its front contact, then resistor 59 is placed in shunt with the space path of the tube 25 and increases the current flow through the coil of relay 1. Upon starting to de-energize the coil, this excess current is cut off by opening 20 the circuit through resistor 59. Thus, when energizing and de-energizing the relay the action is accelerated by the combination of relay contact connections *c* with resistors 28 and 29.

A duplex diode rectifier tube 50 is provided for 25 the purpose of forcing the reversal relay 1 to operate only during periods of program silence. This tube comprises two independent space discharge paths. The electrode group 29 has an anode connected to the back contact associated 30 with relay spring *d*; while the electrode group 30 has a cathode connected to the front contact associated with the same relay spring *d*. Audio signals constituting the output of tube 8 are fed through the voltage dropping resistors 31 and 32 35 to the anode and cathode, respectively, of electrode groups 29 and 30 in tube 50. The cathode of group 29 and the anode of group 30 are connected together and act as the point of zero audio frequency potential connected to a D. C. bias supply through a potentiometer 35. Thus rectified voltages are built up across resistors 36 and 37 with opposite polarity relative to this junction of the rectifier elements. When no audio signals are being rectified, a suitable D. C. bias 40 potential is applied to the grid of tube 25 by virtue of the adjustment of the contact arm on potentiometer 35. With the relay in the non-actuated position the rectified output of the electrode group 29, negative in polarity, is fed 45 through the back contact and spring *d* of relay 1. In the actuated position the rectified output of electrode group 30, positive in polarity, is fed through the front contact and spring *d*.

The lesser of the rectified potentials derived 50 from audio wave peaks of the two phases, that is, from one portion of the tube 10, are continuously subtracted from those of opposite phase, that is, as derived from the other portion of the tube 10. This resultant voltage is utilized in the bias circuit 55 for the tube 25. The control bias circuit for the grid of tube 25 may be traced from the potentiometer 35 through one or the other of the electrode groups of tube 50, depending upon the position of contact *d*, and thence through resistors 21, 22 and 26 to said grid. The energy of

the rectified audio wave peaks is, therefore, superposed on the D. C. bias potential in either of two ways, dependent upon the direction of unbalance between the energies stored in the capacitors 23 and 24, this being a function of the operation of tube 10. The grid bias potential is additionally dependent upon the instantaneous amplitude of the audio signal and its effect upon the action of the tube 50. These rectified potentials, therefore, serve as a control bias potential which is applied to the grid of tube 25 through resistors 21, 22 and 26. The two voltages which are rectified in tube 10, filtered and stored in condensers 23 and 24, are in opposite polarity as connected, one being derived from one half of the applied audio waves, and the other being derived from the reverse side. Thus an unsymmetric wave tends to cause one of these potentials to predominate over the other, giving an increase or decrease of the bias on tube 25.

In order to better illustrate the operation of the device let it be assumed that an audio wave is applied without interruption when relay 1 is in the non-actuated position and that the phase of its dissymmetry is opposed to that of the immediately preceding waves. Then a resultant voltage builds up across resistors 21 and 22 such that the grid end is relatively positive. However, a negative potential is supplied simultaneously from the anode of group 29 in tube 50. This anode is negative and prevents the grid of tube 25 from swinging positive. Thus the relay cannot become actuated as long as the signal is applied without interruption. If, however, a momentary interruption occurs, the discharge across the electrodes 29 in tube 50 ceases instantaneously, there being no appreciable time delay circuits associated with this tube. Since the large storage condensers 23 and 24 hold the charge rectified by tube 10, this interruption causes the grid of 25 to swing positive, thus actuating relay 1 and reversing the phase of the audio signal as applied to the output terminals 51.

When the incoming wave is of opposite symmetry, the action for reversal is as follows: Voltages are built up across the storage condensers 23 and 24 such as to make the grid end of the resistors 21, 22 negative. However, the rectified potential from the cathode of electrode group 30 in tube 50 is of opposite polarity to that of the voltages stored in the condensers 23 and 24 and remains greater in magnitude as long as the incoming signal persists without interruption. The potential from the tube 50 is, in this case, applied through front contact of relay spring *d* to the grid control circuit for tube 25. If then an interruption occurs in the incoming signal the potential created by rectifier tube 50 stops and the grid of tube 25 is swung negative by the previously stored potentials in condensers 23 and 24, causing the relay 1 to release and the phase of the wave to be reversed in its application to the output terminals 51.

Relay contact *e* serves to short circuit an indicator lamp 38 when the relay is in the non-actuated position, thus lighting lamp 39. In the actuated position of the relay, the lamp 38 is not shorted and since it is in series with lamp 39 which is shunted by resistor 40, it is permitted to have more than half of the total lighting voltage. This is sufficient to give a good indication if lamp 38 is covered with a blue or green

glass cap while lamp 39 is covered with red or amber.

Resistors 41, 42 and 43 in the cathode circuits of tubes 5, 8 and 25, respectively, are for purposes of metering. These resistors are low in value, but the voltage drop across any of them is sufficient for producing a reading on the meter 44. The particular circuit to be metered is selected by switch 45.

10 Resistor 46 serves to hold the bias potential applied to the end of resistor 24 approximately the same as that from the potentiometer 35 while the relay contact *d* is traveling from front to back contacts and vice versa.

15 Resistors 47 and 48 are of relatively high ohmic value and serve to bridge the contact groups *a* and *b*, respectively. This is to prevent click noises caused by the input and output circuits assuming different D. C. potentials while 20 switching.

It will be apparent to those skilled in the art that a single amplifier tube might be substituted for the double tube 8. Such a substitution involves merely the adoption of a single-anode output circuit in place of the push-pull circuit shown. Furthermore, the tube 59 might be supplied with energy derived solely from one side, or one anode, of the audio wave amplifier.

30 By comparison with the disclosure of my aforementioned co-pending application, Serial No. 167,709, it will be seen that the instant disclosure presents an embodiment of the invention which is simpler to construct and more 35 economical to maintain. The operation of the device is obtained under improved conditions of efficiency. In the first disclosure of the invention it appeared to be necessary to employ as many as three electromagnetic relays. The same functions are now performed by a single 40 electromagnetic relay. The apparatus, therefore, meets the exacting requirements for reversibly switching the connections between two input terminals and two output terminals without introducing any appreciable "plop" into the speech circuit in which it is preferably employed.

45 My invention is capable of modification in a number of different ways such as might suggest themselves to those skilled in the art. The scope of the invention is, therefore, defined by the claims.

I claim:

50 1. In a switching arrangement for reversing the connections between two input terminals and two output terminals, a relay having operable contacts for making said connections reversibly, means including an electron discharge tube rectifier and an electrostatic storage device for 55 building up a relay energizing force in response to a dissymmetry of audio frequency currents impressed upon said input terminals, and means including a second electron discharge tube rectifier operative in dependence upon the amplitude 60 level of said currents for restraining the operation of said relay until said amplitude level falls to a predetermined critical value.

65 2. Apparatus in accordance with claim 1 and having means including additional contacts operable by said relay and connected through the winding thereof for accelerating its action.

70 3. In switching apparatus for reversing the connections between two input terminals and two output terminals, a single electromagnetic relay having operable contacts for making said con-

nections reversibly, an electron discharge tube circuit arrangement adapted to amplify and to rectify certain components of an audio frequency current impressed upon said input terminals, means for storing the resultant of opposing rectified components derived from dissymmetries of said current, additional rectifying means operable in dependence upon the reduction of said audio frequency current to a predetermined low level for timing the operation of said relay so as to coincide with periods of substantially no current applied to said input terminals, means including other contacts of said relay constituting a single pole double throw switch for connecting said additional rectifying means in aiding or opposing relation to said storing means in accordance with the condition of said relay, and means including a discharge tube in series with the winding of said relay for controlling the times of energizing and de-energizing the same, the last said discharge tube having a grid biasing circuit which includes a direct current source, said additional rectifying means, the single pole double throw switch contacts of said relay and said storing means.

75 4. In a circuit arrangement having input and output terminals, a first rectifier means, a second rectifier means and a solitary relay the winding of which is in series with the space path of an electron discharge tube, the method of controlling the operation of said relay thereby to cause its contacts to reverse the connections between said input and output terminals, which comprises the steps of separately storing the energies derived from the rectification in said first rectifying means of opposing half cycles of an unsymmetric audio wave, rectifying a portion of the energy derived from said audio wave in said second rectifying means for producing a substantially instantaneous response characteristic of differences in the overall amplitude of said audio wave and applying a bias control potential to said electron discharge tube which is the resultant of a fixed bias, a bias determined by said second rectifying means and a bias constituting the difference between the separately stored energies, thereby to produce alternate blocking and discharge conditions in said tube and to reversibly actuate said relay.

80 5. In an audio frequency circuit arrangement having two input and two output terminals, apparatus for reversing the connections between said terminals, said apparatus being operative in response to a reversal in the direction of phase dissymmetry of an audio wave impressed upon said input terminals, a pair of mutually opposing half wave rectifiers connected to said input terminals, capacitive and resistive means for momentarily storing differences between the energies thus rectified, an electron discharge tube 85 having an input circuit including a second rectifier in circuit with a direct current grid biasing source and with said capacitive means, said second rectifier being of the double-diode type and responsive to instantaneous variations in the amplitude of said audio wave, a relay having circuit reversing contacts for completing the first mentioned connections, means including other reversing contacts of said relay for causing said second rectifier to aid or oppose the biasing effect 90 of said storage means, and means including operative connections through said discharge tube and the coil of said relay for causing said input and output terminal connections to be reversed only when a moment of substantially zero am- 95

plitude of said audio wave follows a reversal in the phase of its dissymmetry.

6. A device in accordance with claim 5 and having means for accelerating the action of said relay, said means comprising a resistor in circuit with a pair of contacts of said relay and in shunt with the coil of said relay, whereby upon opening said contacts additional energy is fed through said winding.

10 7. A device in accordance with claim 5 and having means for accelerating the action of said relay, said means comprising a resistor in circuit with a pair of contacts of said relay and in shunt with the discharge tube whose space path is in series with the coil of said relay, whereby, upon opening said contacts, the energy fed through said coil is suddenly reduced.

15 8. An electromagnetic relay having contacts constituting a double pole double throw switch,

said contacts providing reversible connections between two input terminals and two output terminals of an audio wave circuit, means for energizing and de-energizing said relay in response to changes in the direction of phase-dissymmetry of the audio frequency wave impressed upon said input terminals, said means including a pair of mutually opposing half wave rectifiers connected to said input terminals, a device for momentarily storing the differential component of the output energies from said rectifiers, means operative by the resultant of said differential component for increasing and reducing the relay energizing current in dependence upon the direction of shift of said phase dissymmetry, and means controlled by the amplitude of said wave for delaying the action of said relay until a moment of substantially zero current occurs in said audio wave.

JARRETT L. BATHAWAY.
